UNITED STATES PATENT OFFICE.

MARTIN BÜHRE, OF HAMBURG, GERMANY.

BLOCK OF ICE CYLINDER.

Application filed September 15, 1926, Serial No. 135,675. Renewed November 24, 1928.

This invention is directed to a portable refrigerating device designed particularly for the production of ice in blocks, ice cream, or the cooling of liquids in an expeditious and 5 convenient manner.

The principal object of the invention is the provision of a container for the fluid to be cooled or frozen which is adapted to be removably inserted in and seal an insulating 10 outer container, with the temperature reduction induced in the liquid in the inner container by chemicals placed in the outer container to surround the inner container.

The invention is illustrated in the accompanying drawings in which:

Figure 1 is a view in vertical section of the refrigerating device.

Figure 2 is a view in elevation, partly in section, showing the means for clamping the 20 material container in position to seal the refrigerant container.

Figure 3 is a sectional detail illustrating the means for securing the removable cover for the material container in sealed relation to such container.

The improved refrigerating device comprises a refrigerant container including an outer metallic vessel 1 within which is secured a double walled glass lining 2 supported at the lower end by a rubber cushion 3. The lining 2 of double walled formation, as stated, may, if desired, be filled with an insulating material, as for example mercury.

A material container 4, which may be of 35 metal or glass, is adapted to be inserted into the open upper end of the refrigerant container, the material container having its vertical wall 5 upwardly divergent and such container being of a diameter to provide a 40 space 6 between the container and lining of the refrigerant container into which space the chemical refrigerant is introduced.

The material container 4 has an annular bearing section 7 extended laterally and outwardly from the upper edge of the wall 5, the outer edge of the bearing section supporting an integral cylindrical upstanding wall 8. The metallic vessel 1 of the refrigerant container is extended above the lining 2 in the form of an annular flange 9, the interior diameter of which is slightly in excess of that of the vessel 1. A cover 10 is arranged to fit over and close the upper end of the wall 8 and frictionally cooperate at its lower end 55 with the flange 9.

It is important that when the parts are

assembled for use that the material container 4 seal the upper open end of the refrigerant container, and for this purpose there is provided a gasket 11 having an interior 60 opening to snugly receive the material container and of a diameter sufficient to overlie and rest upon the upper end of the lining 2 of the refrigerant container. The bearing section 7 of the material container is formed 65 with an annular depending projection 12 adapted, when the material container is in place in the refrigerant container, to bear upon the gasket 11 in line with the glass lining 2 of the refrigerant container.

Downward pressure is exerted upon the material container to cause this projection to have sealing connection with the gasket through the medium of interconnected levers 70 13 and 14 arranged on opposite sides of the device, the former having a curved upper end 15 passing loosely through an opening 16 in the cover 10 and engaging in an opening 17 in the upstanding wall 8 of the material container.

The lower end of this lever 13 is connected 75 at 18 to the finger lever 14, such connection being beyond the pivotal support 19 of such finger lever, ears 20 projecting in spaced relation from the vessel 1 providing for the 80 pivotal support of the finger lever at 19, as shown in Figure 2. Obviously, in the movement of the finger lever, the operating lever 13 is moved vertically to compel similar movement of the material container to thus 85 seal the latter in position or provide for the 90 convenient removal of such container.

The material container 4 is provided with a closure 21 for sealing the material receiving 95 space of such container at will. The closure which includes a portion to fit within the upper end of the wall 5 is also provided with a vertically offset outstanding lateral flange 100 22 adapted to overlie and rest upon a sealing gasket 23 placed upon the upper surface of the bearing section 7. Clamping means for the closure are provided including a bar 24 loosely connected with the cover by straps 105 25 and adapted to seat at its ends in socket pieces 26 carried by and projecting inwardly from the wall 8 of the material container.

The sockets include upper and lower walls 110 27 and an end wall 28 closing the space between the upper and lower walls at one end of the socket piece. The closing walls 28 are arranged at opposite ends of respective sockets so that the bar 24 may be turned into the

sockets to the limit of the end walls and prevented thereafter from moving in the same direction. A set-screw 29 has threaded connection with the bar 9 and bears upon or may be removably connected to the closure 21.

It will be apparent that when the bar has been turned to seat in the sockets 26, the set-screw may be adjusted to clamp the closure in sealing cooperation with the material container 4. Reverse movement of the screw followed by a swinging movement of the bar 24 to remove the ends from the sockets permits bodily separation of the closure from the container, though of course the container with the closure in sealed position may be readily removed as an entirety from the refrigerant container.

If desired, a handle member or handle members 30 may be connected to the cover 10 for conveniently handling the device as a whole.

In the use of the device, the refrigerant chemicals are introduced into the refrigerant container, following which the material container with the material to be cooled or frozen is introduced into such refrigerant. The closure 21 is applied and sealed in position, the cap or cover 10 is then applied, the operating levers 13 passed through the openings 16 in the cap and fitted into the openings 17 in the material container wall, and the finger levers 14 are turned downwardly to cause a sealing cooperation between the material container and the refrigerant container.

What I claim as new is:

1. A refrigerating device including a refrigerant container, a material container adapted to be seated in the refrigerant container in spaced relation thereto, said material container extending above the refrigerant container and provided with an outwardly extending flange and an upstanding wall, a sealing gasket carried by the refrigerant container and adapted to be engaged by the outwardly extending flange of the material container, a closure for the container

which overlies the outwardly extending flange, a gasket interposed between the closure and the outwardly extending flange, means including a bar having interlocking connection with the upstanding wall, and a screw between the bar and closure to clamp the latter to the material container, and means carried by the refrigerant container to engage the upstanding wall of the material container above the refrigerant container to clamp the material container in sealing cooperation with the refrigerant container.

2. A refrigerating device comprising a lined vessel to receive the refrigerant, a container to receive the material to be treated, said container having a bearing portion to overlie the upper end of the vessel and a wall extending above the bearing portion, a gasket between said bearing portion and the vessel, a cover fitting over the upstanding wall of the material container and the upper end of the vessel, levers supported by the vessel and adapted to pass through openings formed in the cover and engage said upstanding wall of the container to force the bearing portion into sealing cooperation with the gasket, a closure for the container, and means for sealing the closure in place.

3. A refrigerating device comprising a lined vessel to receive the refrigerant, a container to receive the material to be treated, said container having a bearing portion to overlie the upper end of the vessel and a wall extending above the bearing portion, a gasket between said bearing portion and the vessel, levers supported by the vessel and adapted to engage said upstanding wall of the container to force the bearing portion into sealing cooperation with the gasket, a closure for the container, a bar carried by the closure, sockets carried by the upstanding wall of the container to receive the end of the bar, and a set-screw inserted through the bar and exerting endwise pressure upon the closure.

In testimony whereof I affix my signature.

MARTIN BÜHRE.
